CONDIMENT DISPENSER OR THE LIKE

Ruediger W. Knott, Corning, N.Y., assignor to Corning Glass Works, Corning, N.Y., a corporation of New York

Filed July 21, 1964, Ser. No. 80,950

Term of patent 14 years

(Cl. D44—22)

Fig. 1

Fig. 2

Fig. 3

I claim:

The ornamental design for a condiment dispenser or the like, as shown.
